Primary Examiner — Mary Ann Calabrese*Assistant Examiner* — Natalya M Rapundalo(74) *Attorney, Agent, or Firm* — Eric Karich; Karich & Associates(57) **CLAIM**

The ornamental design for a fermentation crock, as shown and described.

DESCRIPTION

FIG. 1 is a perspective view of a fermentation crock, in an exploded configuration, showing my new design;

FIG. 2 is a perspective view of the fermentation crock, in a closed configuration, showing my new design;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines and the area within them shown in the drawings represent portions of the fermentation crock and form no part of the claimed design.

1 Claim, 8 Drawing Sheets(56)
